ATTORNEY

UNITED STATES PATENT OFFICE.

ALBRECHT HEIL, OF FRÄNKISCH CRUMBACH, GERMANY.

WRITING-RECEIVER.

SPECIFICATION forming part of Letters Patent No. 503,371, dated August 15, 1893.

Application filed January 21, 1893. Serial No. 459,267. (No model.)

To all whom it may concern:

Be it known that I, ALBRECHT HEIL, a subject of the Grand Duke of Hesse, residing at Fränkisch Crumbach, in the Grand Duchy of 5 Hesse, German Empire, have invented new and useful Improvements in Writing-Receive-
ers, of which the following is a specification.

My invention has reference to an instru-
ment adapted for beginners in learning teleg-
raphy, as well as for preparing documents or
messages in a secret writing composed of dots
and dashes like those of the Morse alphabet.

It has for its object to provide in a simple
instrument both a receiver and a transmitter,
without the use of electro-magnets or an elec-
tric current.

The nature of my invention will best be un-
derstood when described in connection with
the accompanying drawings, in which—

20 Figure 1 represents a front elevation of an
instrument constructed according to my in-
vention. Fig. 2 is a detail view showing the
arrangement and connection of the key. Fig.
25 3 is a plan or top view thereof, the base being
omitted. Fig. 4 represents detail views of a
form of pen adapted for use in the instrument.

Similar letters of reference designate corre-
sponding parts throughout the several views
of the drawings.

30 In the drawings the letters T T' designate
a key similar in construction to those usually
employed in telegraphic transmitters, but
formed without particular reference to the
making and breaking of a circuit. It is con-
35 nected by a link N with a lever H pivoted at
p to a post M. At the outer end of the lever
H is connected a spring pressed pawl m
adapted to engage with a ratchet wheel r
mounted on a horizontal shaft s' provided
40 with a flywheel S. Intermediate of said pawl
and the point of pivoting of the lever H is
attached a downwardly projecting tappet n
adapted to engage one end of a spring lever
o carrying at its opposite end a pencil or ink
45 style d arranged opposite to the tape roll or
platen f. The paper tape q conducted from
the reel (not shown), is passed over a guide
roll a and about the platen f. It is fed for-
50 ward by a small feed roll c on the shaft of
the ratchet wheel r as will be presently ex-

plained. The instrument is operated in sub-
stantially similar manner to the telegraph in-
struments now in use, the letters of the Morse
alphabet being produced on the tape by de-
pressing and releasing the key T T'. At each 55
depression of the key the pawl m engages
the ratchet wheel r and turns the same, there-
by turning the two rolls c and f to advance
the tape. In view of the inertia of fly wheel
S the rolls continue to revolve for a short 60
period of time. The tappet n at the same
time engages the lever o and throws the pen-
cil or style d into contact with the tape q.
The pencil is held in this position until the
key is released, whereupon the spring o' ele- 65
vates the key and the tappet n disengages
the lever o. The tape q having continued to
advance during the time that the pencil or
style was in contact with the same, a corre-
sponding mark is produced thereon. The 70
mark will be either a dot or a dash according
to the length of time during which the key is
held depressed.

In practice I prefer to use an ink style such
as shown in Fig. 4, the same consisting of a 75
trough shaped metal tip formed with a
rounded end which forms the writing point.
The style can be conveniently made by bend-
ing up a blank, as d', about its longitudinal
center line. This style I find gives good re- 80
sults and can be readily and easily cleaned.

What I claim as new, and desire to secure
by Letters Patent, is—

1. In an instrument of the character speci-
fied, the combination of a platen and feed 85
roll for the tape, a pencil or style lever adapt-
ed to the platen, a key, and operative con-
nection between the key and the feed roll
for advancing the tape on the depression of
the key, and a tappet arranged to engage 90
with the pencil or style lever and in opera-
tive connection with the key, substantially as
described.

2. In an instrument of the character speci-
fied, the combination of a key, a feed roll and 95
platen for the tape, a ratchet wheel for the
feed roll, a pencil or style lever adapted to
the platen, a lever provided with a pawl ar-
ranged to engage the ratchet wheel, and with
a tappet arranged to engage the pencil or 100

style lever, and a connection between the key and said lever, substantially as described.

3. In an instrument of the character specified, the combination of a key, a platen, a feed roll *c*, a fly wheel *S* and ratchet wheel on the shaft of the latter, a pencil or style lever, a lever *H* provided with a pawl engaging the ratchet and with a tappet adapted to engage the pencil or style lever, and a link connect-

ing the key and lever *H*, substantially as described.

In testimony whereof I have signed my name to this specification in the presence of two subscribing witnesses.

ALBRECHT HEIL.

Witnesses:

JEAN GRUND,
FRANK H. MASON.
